UNITED STATES PATENT OFFICE.

JOHN DUBREE, OF DRUMORE TOWNSHIP, LANCASTER COUNTY, PA.

IMPROVED HITCHING-STRAP.

Specification forming part of Letters Patent No. 56,537, dated July 24, 1866.

To all whom it may concern:

Be it known that I, JOHN DUBREE, of Drumore township, in the county of Lancaster and State of Pennsylvania, have invented a new and Improved Combined Safety-Bridle and Hitching-Strap; and I do hereby declare that the following is a full, clear, and exact description thereof, reference being had to the accompanying drawings, making part of this specification, in which—

Figure 1 is an application of the same on a horse; Fig. 2, the two parts or three separate pieces of my invention. Fig. 3 illustrates the mode of their application to a headstall or common bridle. Fig. 3 bis. is a perspective view of one side with a portion of the bridle.

The object of my invention is to prevent horses from breaking the reins or hitching-strap, as well as to control them while driving, for which purpose various devices have been invented involving a common principle of known utility, my arrangement of the parts differing in construction and application, which I will now proceed to describe, so as to enable any one skilled in the art to make and use my invention.

Fig. 3 shows a common headstall or bridle without a bit, representing in outline also the application of Fig. 2 detached. The cheek-pieces J are terminated by a ring, L, and provided with a buckle, K, as shown; two straps, C' C'', provided with a ring at one end and a single strap, (of leather,) G, with a ring, E, and hitching-strap F at its center.

The loose bit B and straps C and G are at-

tached to the bridle thus: One end of the strap G is first passed through the ring L on the cheek-piece J, then through the ring A on the bit on one side of the bridle, then through a loop and buckle, K, on said cheek-piece, and secured. The other end of the strap G is passed through the rings L A on the other side and secured in like manner. This is the attachment of the hitching-strap F, combined with the single strap G. The two ring-straps C' C'' are then simply passed through the ring A of the bit, one on each side, as shown, and also passed through the loop and buckle K on the cheek-piece J. Thus secured the safety-bridle and hitching-strap is completed. The reins or lines are then attached to the rings D on the end of each of the straps C' C''.

I am aware that a hitching-strap is used connected with the throat-latch and rings of the bit over the horse's head. Such I do not claim; nor do I claim a single safety-strap, nor when of two pieces it is connected to the bit and carried up through a ring or buckle on the cheek-piece and down again through the ring of the bit.

What I claim as my invention, and desire to secure by Letters Patent, is—

The simple strap G for the attachment of the hitching-strap F, when said strap G is connected with the bridle and bit in the manner and for the purpose specified.

JOHN DUBREE.
